UNITED STATES PATENT OFFICE

2,455,759

METHOD OF MANUFACTURING SYNTHETIC
BRISTLES FOR BRUSHES

John J. Gregory, Creighton, Pa., assignor to Pittsburgh Plate Glass Company, Allegheny County, Pa., a corporation of Pennsylvania

Application April 28, 1944, Serial No. 533,206

5 Claims. (Cl. 300—21)

1

This invention relates to the manufacture of synthetic filaments and it has particular relation to methods of measuring, cutting and preparing synthetic filaments adapted to be employed as bristles in the manufacture of brushes, or for other purposes.

The invention herein disclosed constitutes a continuation-in-part of my copending application Serial No. 499,264, filed August 19, 1943, now Patent 2,356,841, of August 29, 1944, for Filament cutting apparatus.

One object of the invention is to provide an improved method of cutting synthetic filaments to predetermined lengths.

Another object of the invention is to provide an improved method of cutting filaments that are tapered at intervals and preparing them for assembling and further cutting to lengths according to the taper therein so as to insure the proper bristle arrangement for incorporation thereof into a brush.

Another object of the invention is to provide an improved method of cutting and bunching or bundling synthetic tapered bristles.

In one form of the invention for producing bristles for brushes, synthetic filaments are received continuously from a filament forming machine, such as that shown and described in my copending application Serial No. 459,251, filed September 22, 1942, now Patent No. 2,374,744 of May 1, 1945. The filaments, which are tapered at intervals, are produced continuously at a constant rate from this machine and are received upon a suitable surface along which they can be guided. Since the filaments are tapered at intervals, the variation in thickness thereof can be utilized to make and break electric contacts when the thicker portions pass a predetermined point. These contacts are connected to an electric cutting device which is operable to sever the filaments when it is electrically energized. The relative positions of the cutting device and the guiding surface and the distance between thicker portions of the tapered filaments can be coordinated to control the cutter so as to sever the filaments regularly either at the location where they are thicker or at the location where they are thinner.

In connection with one form of the invention, it has been found that very satisfactory results can be secured by cutting the filaments approximately at the location of their maximum thickness. Although the filaments can be extruded in smaller or larger form according to the fineness or coarseness of the brush in which the finished bristles are to be incorporated, they are, regardless of size, resilient and inherently springy to such degree that they tend to remain straight or extended. The bristles are first cut at the location of the maximum diameter

2

or thickness and can be collected and bound in bunches or bundles of double length with the smaller portions receiving the binding tape, or the like, so that the butts or larger cut portions are disposed at opposite ends of each bundle. In this way the location of the smaller portions are readily discernible and the cut and bundled bristles can be laid aside or stored pending their incorporation into brushes. Since the inner areas are together each bunch can be held thereby, and if there are any broken pieces or scraps of filaments which are to be discarded they can be removed by combing them out or by any other suitable method. When the bristles are to be incorporated into brushes the bundles are cut at the bound thin portions by shears, or otherwise, and their proper relation maintained.

In the drawing:

Fig. 1 is a diagrammatic elevation of a filament cutting apparatus; Fig. 2 is a fragmentary elevation, on a larger scale, of electric make and break contacts with supports therefor; Fig. 3 is a vertical section taken substantially along the line III—III of Fig. 2 and with parts shown in elevation; Fig. 4 is a view similar to Fig. 3 with parts shown in different positions; Fig. 5 is a horizontal section taken substantially along the line V—V of Fig. 1 and with cutter structure shown in plan; Fig. 6 is a side elevation of the structure shown in Fig. 5 looking in the direction of the arrows on line VI—VI of Fig. 1; Fig. 7 is a fragmentary vertical section, on a larger scale, of a tubular guide including air directing parts; Fig. 8 is a fragmentary horizontal section taken substantially along the line VIII—VIII of Fig. 7; Fig. 9 is a diagrammatic plan of a bundle of filaments cut to double length sections; Fig. 10 is a diagrammatic plan of a synthetic bristle; Fig. 11 is a fragmentary perspective of a bundle of filaments with shears for cutting them; and Fig. 12 is a fragmentary view, similar to Fig. 11 of a bundle of bristles after the bristles have been severed.

In practicing the invention a drum 10 is rotatably mounted upon a horizontal disposed driven shaft 12 which rotates in suitable bearings 14 on a supporting frame 15. A motor 16 having suitable reduction gearing 19 connecting it to the shaft provides power for rotating the drum.

Filament stock 20, which can be in the form of one or a group of filaments, is received from a source of supply, such as a filament producing machine described in my copending application Serial No. 459,251, above referred to, and such stock is guided over an idle roll 23 carried upon a pin 24 in a bracket 26 on the frame 15. From the filament producing machine, fifty to several hundred filaments can be extruded simultaneously, depending upon the type of extrusion head or

spinnerette used and the size or denier of the filaments to be formed.

From the idler roll 23 the filaments are directed between the drum 10 and weighted rolls 28 and 29 which are rotatable upon horizontal bearings 30 forming the lower portions of hangers 31 that have pivotal connections 32 suspending them upon the upper portion of the frame 15. An arm 34 rigidly connected to the lower portion of each hanger extends laterally therefrom and is provided with a weight 35 adjustably mounted thereon by means of a set screw 36 passing therethrough into contact with the arm. The rolls thus mounted tend to swing toward the drum to confine and guide the filaments yieldably under pressure against the surface of the drum. These rolls 28 and 29 are disposed substantially on opposite sides of the drum slightly below the horizontal center line thereof, and the filaments 20 pass from the roll 28 over the upper peripheral surface of the drum. They then pass downwardly between the roll 29 and drum through a tube 40 that is rigidly mounted on the frame 15 by means of a bracket 41 rigidly carried thereby.

The tube 40 is disposed substantially vertically and is partially flattened at its lower end to form a slot-like exit opening 42 (Fig. 7). The upper end portion of the tube has formed thereon a hollow head 43 provided with a circumferential channel 45 which is surrounded by a collar 46 mounted by sweating it upon the head so as to provide an air-tight fit thereon in covering relation to the channel. Air directing ducts 47 lead from the channel 45 in a downward direction and open through the inner walls of the tube. A nipple 49 connected to the collar and communicating with the channel 45 is adapted to be connected to a suitable air pressure source (not shown) for the purpose of streaming air downwardly through the ducts 47 and downwardly through the tube.

Immediately below the lower end of the tube 40 a cutting device 50 is mounted by welding or otherwise securing a plate portion 51 thereof upon the frame 15. This plate also includes a stationary horizontal blade 52 rigidly carried thereby and has a pivot pin 53 mounted thereon to support a bell-crank 54. One arm 56 of the latter includes a knife 57 arranged to cooperate in shearing relation with the blade 52. The other arm 59 of the bell-crank is connected by means of a tension spring 60 to a lug 61 that is welded to the lower side of the plate 51. This spring normally holds the knife in open position. A set-screw 62 threaded through the lug 61 limits the pivotal movement of the bell-crank to prevent excessive opening of the knife. If desired, a compression spring 63 can be mounted on the pin 53 to maintain the bell-crank pressed against the plate 51 and in proper position to insure close contact between the blade 52 and knife 57 when they are moved in cutting relation. The terms blade and knife are employed to differentiate parts of the cutter structure although these elements perform substantially the same function. The outer end of the lever arm 56 is pivotally connected, as indicated at 64, to one end of a link 65, the other end of which is pivotally connected, as indicated at 67, to the outer end of a core 69 that forms a part of a solenoid 70. The latter is rigidly connected to the plate 51 by means of welding or the like.

As the filaments are directed upwardly over the periphery of the drum 10, they pass beneath a feeler roll 80 rotatably mounted, as indicated at

81, on one end of a lever 84 that has an intermediate pivotal connection 86 securing it on an upright adjustable frame 87. The lower portion of the frame 87, which includes an upright bar 90, is pivoted upon one of the bearing members 14 with its axis of pivoting coincidental with the axis of the driven shaft 12. An adjusting bolt 91 passes through the bar and through one of a series of openings 92 in an upright plate 94 that is rigidly mounted upon the apparatus frame 15. This arrangement provides for adjusting the frame 87 to the right or left, as viewed in Fig. 1, about the axis of rotation of the drum 10.

The end of the lever 84 opposite the mounting 15 of the roll 80 has a pivotal connection 96 securing it to one end of an adjustable link 97, the other end of which is connected, as indicated at 98, to the outer end of an electric contact lever 100. The adjustable link includes opposite end heads 101 into which the shank of the link is screw-threaded in opposite directions so as to move the heads toward or away from each other, depending upon the direction of turning of the shank of the link. An intermediate portion of the contact 20 lever 100 has a pivotal connection 102 securing it to the adjustable frame 87.

The lever arrangement described above constitutes an actuating mechanism for making and breaking resilient contacts 104 and 105 of inverted 30 U-shape which are mounted on the outer end of the lever 100 and on a bracket 106, respectively. The latter bracket 106 is rigidly mounted upon the frame 87. The free end of the contact 104 is in the form of a horizontal finger 109 which is 35 adapted to engage the other contact 105. Insulating blocks 112 and 113 forming end portions of the lever 100 and bracket 106 support the contacts 104 and 105, respectively, which are connected by conventional wiring 114 to a magnetic 40 switch 116 through which electrical connection is established to the solenoid 70 (included in the wiring 114) and to electric mains 117. Connection to the mains is controlled by a switch 118.

It will be observed that the levers 84 and 100 45 are so mounted that the degree of movement of the contact 104 on the outer end of the lever is greatly increased with respect to the movement of the roll 80 in response to movement of the larger portions of the tapered filaments 20 thereunder. When the larger portions of the filaments pass underneath the roll 80, the finger 109 is raised and in traveling upwardly it strikes a sloping under surface of a cam 120 that is formed upon the outer end portion of the insulating member 113. The finger 109 continues this movement until it is sprung outwardly and snaps over the upper edge of the cam to the position indicated in broken lines of Fig. 3. As the larger portions of the filaments pass from beneath the roll 80 the finger 109 drops against the contact 105 to the position shown in Fig. 4 and completes the electric circuit to energize the solenoid 70 and to operate the knife 57, thereby severing the filaments 20. This action is rapidly consummated and the knife 57 is immediately re-opened to such position that the next length of filaments to be cut continues past the knife until the thicker filaments again actuate the roll 80 to initiate a repetition of the operation described. 55 In order that the filaments may not recoil or otherwise disarrange themselves before or after the cutting operation, air under pressure is 60 streamed downwardly through the tube 40 from the ducts 47. The action of the air continuously 65 draws the filaments toward the area of cutting. 70

The frame 87 can be adjusted to vary the distance from the point of contact of the roll 80 with the filament stock to the cutter. Such adjustment provides for cutting the filaments at the proper location and to provide for proper cutting of filaments which have different lengths of tapered sections from those shown in the drawing.

It is to be understood that the group of filaments are supplied and fed to the drum 10 in such manner that a thicker portion of any filament lies together with thicker portions of adjacent filaments. Thus the filaments as a group have successive thicker and thinner areas or sections. In the particular arrangement and adjustment of elements indicated in the drawings, the cutter severs the filament stock or group of filaments at their maximum thickness which, after cutting, constitutes butt ends 130. The smaller or thinner sections remain intact to be severed subsequently. As the successive sections of filaments are cut they are gathered manually and bound by a thin band 131 of adhesive coated paper, Scotch tape, or the like, at the location of the thinner portions. For the sake of clarity it is to be understood that an interval of tapering is intended to define an interval between successive thicker portions of the filament or between successive thinner portions of the filament. Single length bristle includes the distance from an area of maximum thickness to an area of minimum thickness. Each interval of tapering therefore includes a double length bristle section, that is, a double length section can be cut into two bristles of tapered form. Double lengths of bristles are thus collected in bunches or bundles 134 and since their larger butt ends are arranged together and their thinner portions, which are later to be severed, are also together, such arrangement facilitates the maintenance of the bristles in proper relation. By grasping the thinner portions an operator can remove by combing out, or otherwise, any loose bristle fragments or other foreign matter that it may be desirable to discard. Likewise, the butt ends can be maintained in proper transverse relative alignment. Such control in handling the bristles would be difficult in the event that they were originally cut to their final lengths, because loose tapered bristles require more than casual observation to discern their tapered form. Before the bristles are to be incorporated in a brush they are cut by shears 135, or otherwise, as indicated at 136 at their thinner portions. The cut is made through the binding band 131 of paper, or the like. A portion of the band thus remains upon the smaller tapered ends of the bristles after being cut to the length required for incorporation into the brushes, and holds the bristles temporarily in bunched relation.

Although only one form of the invention has been shown and described in detail, it will be apparent to those skilled in the art that the invention is not so limited, but that various changes can be made therein without departing from the spirit of the invention or from the scope of the appended claims.

I claim:

1. In a method of cutting tapered synthetic bristles to measured lengths from continuously fed bristle stock composed of successively tapered portions, the steps which comprise shearing the bristle stock to double length bristle sections at intervals according to the intervals of tapering, gathering the cut double length sections of stock

with thinner portions of all the cut sections bunched together, subsequently further cutting the sections to single length bristles while maintaining together the respective thinner and thicker portions preparatory to incorporation of the bristles into a brush.

2. In the manufacture of tapered synthetic bristles for brushes, the method which comprises cutting a filament, composed of successive linearly tapered sections, at the thicker filament portions to leave the thinner portions intact and further leaving the bristle sections in double lengths, gathering the cut filament sections and binding them with their thinner portions together, and cutting the bound filaments substantially midway between the section ends and at their thinner portions to produce single length tapered bristles.

3. In the manufacture of tapered synthetic bristles for brushes, the method which comprises feeding recurrently tapered synthetic filaments as a group along a predetermined path with the filaments as a group constituting a recurrently tapered mass of filament stock having alternate thicker and thinner areas along its length, cutting the stock at the thicker areas to form double-length bristle sections, gathering the double-length bristle sections into bundles, binding the sections around their thinner portions with thicker portions thereof extending in opposite directions, and cutting the bound filaments substantially midway between the section ends and at their thinner portions to produce single-length tapered bristles.

4. In the manufacture of tapered synthetic bristles for brushes, the method which comprises cutting a filament, composed of successive linearly tapered sections, at the thicker filament portions to leave the thinner portions intact and further to leave the sections in double length bristle form, gathering the cut filament sections and binding them with a band of thin material secured around the thinner portions of the gathered filaments, cutting the bound filaments and the band thereby leaving sections of the band secured on end portions of the severed sections to hold them in assembled relation and in single-bristle length after the latter cutting operation.

5. In a method of preparing tapered synthetic bristles for incorporation into brushes, the steps which comprise continuously feeding recurrently tapered bristle stock along a predetermined course so that thicker and thinner portions of the stock pass successively a predetermined location, cutting the bristle stock at the thicker portions to form double length bristle sections, gathering the double length bristle sections and bundling them with the thinner portions of the sections together and the thicker portions together, and subsequently cutting the bristle sections at the thinner portions to form single length tapered bristles.

JOHN J. GREGORY.
